United States Patent Office

Des. 197,449
Patented Feb. 4, 1964

197,449

COMBINED DISPLAY AND STORAGE STAND FOR PACKAGES OR THE LIKE

Albert M. Travis, Bonner Springs, Kans., assignor to Henry Field Seed & Nursery Company, Shenandoah,
Iowa, a corporation of Iowa

Filed Mar. 8, 1962, Ser. No. 69,140

Term of patent 14 years

(Cl. D80—9)

Fig. 1.

Fig. 2.

FIG. 1 is a front perspective view taken from one side of a combined display and storage stand for packages or the like embodying my new design; and

FIG. 2 is a rear perspective thereof taken from the side opposite that shown in FIG. 1.

I claim:

The ornamental design for a combined display and storage stand for packages or the like, as shown.
